United States Patent Office.

WILLIAM O. REID, OF VIENNA, NORTH CAROLINA.

Letters Patent No. 100,324, dated March 1, 1870.

IMPROVED ADJUSTABLE BEDSTEAD.

The Schedule referred to in these Letters Patent and making part of the same.

To all whom it may concern:

Be it known that I, WILLIAM O. REID, of Vienna, in the county of Forsyth, and State of North Carolina, have invented a new and improved Adjustable Bedstead; and I do hereby declare that the following is a full, clear, and exact description thereof, which will enable others skilled in the art to make and use the same, reference being had to the accompanying drawings forming part of this specification.

This invention relates to improvements in beds for sick persons, and consists in an arrangement of the bottom in three sections, and jointing them together, and supporting them on a transverse axis mounted in the side rails of the bedstead, and providing therewith novel arrangements of supporting and adjusting-arms and hoisting and adjusting-cords and pulleys, whereby the patient may, while lying on the bed, raise himself to a sitting position, with the feet projecting below the plane of the bottom of the bed, which assumes the position of a large chair, and whereby also he may, while lying on the bed, raise the thighs to a perpendicular position, the lower edges remaining in a horizontal position.

The said improved bed is particularly adapted for the treatment of diseases requiring the patient to be changed and placed in particular positions, which changes are greatly facilitated by it.

Figure 1 is a longitudinal sectional elevation of my improved adjustable bed, and

Figure 2 is a side elevation of the bottom and some of the adjusting devices, detached from the bedstead, showing the position for maintaining the thighs in the vertical position, when the patient is lying on the back.

Similar letters of reference indicate corresponding parts.

A is the frame of the bedstead, the parts B of which rise to a sufficient height to support the cords C D, by which the operator effects the changes in a convenient position above him.

The bottom is made in three sections E F G, which are hinged together, and at the joint between the parts E and F they are journaled to a transverse shaft, H, mounted in the side rails of the bedstead.

The part E is provided at the under side with a strong arm, I, attached so as to project well toward the foot of the bedstead and near to the floor.

At this lower end it is provided with one or more grooved pulleys, K, over which the elevating and lowering cord C, which is attached to the bedstead at L, works, and also works over other pulleys attached to the bedstead at M; thence it passes up over the pulley N, and along a grooved support, O, at the other end of which it hangs above the bed, so as to be reached by the occupant.

This arm I also carries a crooked and curved brace,

P, pivoted to it at u, and to the part G of the bed-bottom at v.

Below the central part F of the bottom, an I near the shaft H, is a rock-shaft, W, having two wipers, X, rigidly attached and bearing against the under side of the said part F, so as to raise it when the shaft is turned. This is effected by means of the arms y, projecting downward and toward the head, and carrying a grooved pulley at the end, over which the actuating-cord D, attached to the bedstead at z, works, and passes back over pulley z' thereat; thence over a pulley at M, and up over the top in the same way that the cord C does.

Within the channels or grooves O, for these cords, are weighted holding-pawls y', one for each, resting on the cords, and so arranged that they will permit the cords to be drawn up, but will hold them from going back, unless raised, and they are provided with pendant cords x', working over guide-pulleys for raising them.

The occupant of the bed may raise himself up to a sitting position, and cause the bottom to assume the form of a chair, with a foot-stool attached, by pulling up the cord C, which will, through the medium of the arm I and brace P, raise the part E and depress the part G of the bottom.

The positions which they will assume are represented in dotted lines at E' and G'.

G² is the foot-board attached to the part G so as to move down with it, as shown dotted at G³, and serve as a foot-stool.

In fig. 2, F', G⁴, and G⁵ represent the positions which the parts F, G, and G² may be caused to assume by pulling up the cord D, through the medium of the arm u and rock-shaft W, and wipers X, when it may be desired to raise the thighs to the vertical position, for surgical or other purposes.

The part F is provided with a hole, closed by a stopper, B', hinged to the said part, and secured in the closed position by a spring catch, and below this is placed a shelf, B², on which a bed-pan may be placed; for use in a way to relieve the patient materially. This part is so supported that it will in no case swing downward.

When the bed-bottom is raised up to the position of a chair, the occupant may step out at the foot to the floor very conveniently. By means of the cord O and holding-pawl, the parts E and G may be sustained in any required inclination.

C¹ represents supports for medicine or other light articles, suspended within reach of the patient, when lying down, by the turning rods C², and D¹ is a table, connected detachably to the foot-posts, and suspended at the front by rods D², so that it may be swung up to the top of the bedstead out of the way, when not required for use by the patient, who can, when sitting up, reach things placed thereon for his use.

Having thus described my invention,

I claim as new, and desire to secure by Letters Patent—

1. The combination with the bed-bottom, made in three parts, and hinged together as described, of the shaft H, arm I, brace P, and operating-cord c, and pulleys, substantially as specified.
2. The combination with the parts F G, hinged to the part E of the rock-shaft W, wipers X, arm u, the brace P, and the operating-cord D, and pulleys, all substantially as specified.
3. The combination with the cords C D, arranged for suspension over the top of the bed, as described, of

the weighted pawls u' and lifting-cords z', all substantially as specified.

4. The combination with a bed, arranged to fold up and support the patient in a sitting position, of the table D', detachably connected to the foot-posts, and suspended by rods D', arranged for swinging the table up to the top of the frame, all substantially as specified.

WILLIAM O. REID.
